UNITED STATES PATENT OFFICE.

LAURANZ BARBALICH, OF CLEVELAND, OHIO.

DESIGN FOR A TOP.

50,980.

Specification for Design.

Patented July 3, 1917.

Application filed April 25, 1917. Serial No. 164,570. Term of patent 7 years.

To all whom it may concern:

Be it known that I, LAURANZ BARBALICH, a citizen of the United States, residing at Cleveland, in the county of Cuyahoga and State of Ohio, have invented a new, original, and ornamental Design for a Top, of which the following is a specification, reference being had to the accompanying drawing, forming part thereof.

The figure is a view in front elevation of a top, showing my new design.

I claim:—

The ornamental design for a top, as shown.

LAURANZ BARBALICH.

Witnesses:

JOHN WEIZER, Jr.,

JOHN CUJMADIOI.
